US0D1112696S

(12) **United States Design Patent** (10) Patent No.: **US D1,112,696 S**
(45) Date of Patent: ** Feb. 10, 2026

(54) **FAN**

(71) Applicant: **GD Midea Environment Appliances MFG Co., Ltd.**, Zhongshan (CN)

(72) Inventors: **Junxiong Xiao**, Guangdong (CN);
Yingwen Huang, Guangdong (CN)

(**) Term: **15 Years**

(21) Appl. No.: **35/523,683**

(22) Filed: **Jan. 23, 2024**

(80) **Hague Agreement Data**

Int. Filing Date: **Jan. 23, 2024**

Int. Reg. No.: **DM/235526**

Int. Reg. Date: **Jan. 23, 2024**

Int. Reg. Pub. Date: **Jan. 24, 2025**

(30) **Foreign Application Priority Data**

Oct. 18, 2023 (CN) 202330675299.0

(51) **LOC (15) Cl.** 23-04

(52) **U.S. Cl.**

USPC **D23/378**

(58) **Field of Classification Search**

USPC D23/370, 378, 381, 383

CPC F04D 17/04; F04D 25/10

See application file for complete search history.

(57) **CLAIM**

The ornamental design for a fan as shown and described.

DESCRIPTION

- 1. Fan
- 2. Fan
- 1.1 : Front
- 1.2 : Back
- 1.3 : Left
- 1.4 : Right
- 1.5 : Top
- 1.6 : Bottom
- 1.7 : Perspective
- 2.1 : Front
- 2.2 : Back
- 2.3 : Left
- 2.4 : Right
- 2.5 : Top
- 2.6 : Bottom
- 2.7 : Perspective

The design product is used for circulating air. No color is claimed in this application.
